UNITED STATES PATENT OFFICE.

KARL KIEFER, OF CINCINNATI, OHIO.

FILLING MACHINE.

Application filed January 2, 1920. Serial No. 348,860.

To all whom it may concern:

Be it known that I, KARL KIEFER, a citizen of the United States, residing at Cincinnati, in the county of Hamilton and State 5 of Ohio, have invented certain new and useful Improvements in Filling Machines, of which the following is a specification.

My invention relates to that class of filling machine where containers are filled automatically to a certain height, and where bottles are lifted and lowered to the filling mechanism proper. My mechanism thus belongs particularly to that class of machinery which fills two kinds of liquids, such as 15 syrups first and then carbonated water afterwards; and to that class of machinery where filling is done under a pressure different from the atmosphere.

It consists also of novel filling mechanism 20 and other parts, such as described further in detail.

In the drawings:

Fig. 1 is an upright view of part of the mechanism and a vertical cross section of 25 other parts of the mechanism in the same figure;

Fig. 2 shows a detail of the star feed.

The filling machine consists of the main base A which carries the interior main bearing for the table B and filling mechanism C. The tank is adjustable as to the distance 30 from the table as in the manner of the filling machine shown in Fig. 3 of my Patent No. 1,017,418 of Feb. 13th, 1912, and I need not, therefore, describe these details disclosed by 35 a prior patent.

The bottle lift in my present invention has the desirable feature that when the bottle is pressed against the filling tube D, 40 whereby spiral springs 2 have to be compressed so as to effect an air tight seal on the bottle, then the lifting capacity of this bottle lifting mechanism is multiplied in proportion to the increased power that is required 45 to compress said springs. A mechanism producing similar results I have had patented to me in a non-rotary filling machine, Patent No. 1,115,834 of Nov. 13, 1914, that consists of a combination of lifts. The 50 same desirable results I receive in rotary filling machines by a crank F mechanism having preferably three arms.

In Fig. 1, E is a bearing for this triple crank F. The bottle racks consist of the 55 forks G in which bottle table 3 is carried by means of the shaft 4. These forks have

a lower surface and carry hooks 5 that swing in these forks by means of round pins 6. Only a few of these bottle racks and lifts are shown so as not to obscure the drawing. 60

The shaft parts 4 move in openings in the table B. In these openings are tubular projections 8, some of them shown in Figs. 1 and 2, which serve another purpose to be described later. 65

The fork is guided against the spider casting H by means of rollers 9, which allow the bottle forks G to freely move up and down. Fastened upon the same column that carries the table B and the spider H is a large bevel gear K into which engages a small bevel pinion 10 that is fastened upon the same shaft as the crank F and therefore effects the movement of this crank. 70

The table of the machine is shown in the drawing to move from right to left, that is, while looking down upon the whole mechanism, in the direction of a clock. It is plainly evident from the drawings how the bottle racks G are raised by means of this crank. 75 Rollers 12 are located on the ends of this triple crank to reduce the friction. It is necessary to time the small bevel pinion 10 and the large bevel gear K so that one of the crank arms of the triple crank F corresponds in its motion to one bottle rack G. 80

For instance, if I have a machine with 24 bottle racks, the crank F has to make eight revolutions. More or less than three arms might be used in this crank mechanism, but 85 I obtain good results from this triple crank. It is evident that when the bottle rack is approximately at its highest position the upper crank arm exerts a greater force upon these bottle lifts and easily compresses the 90 springs. It is also evident that at the lowest position these crank arms start their work of lifting these bottle racks much easier and start the lifting of the bottle without any jar, increase their speed and presses 95 the bottle with increased force against these springs. When the bottle rack is at its greatest height and the bottle is pressed against the seal, these bottle racks G are locked by means of the hooks 5 which engage the spider casting as shown at the extreme left of the drawing. These hooks have two surfaces at an obtuse angle, the upper surface 13 being the edge of a middle vertical rib, and the lower surface 14 being 100 flat. The upper surface 13 is engaged by a 105

spring 15 which lifts the hook into position 110

shown at the extreme left. The lower ring of the bottle rack does not require any different mechanism than is shown in patent to me No. 1,017,418 of Fig. 1; it will roll down an inclined way L. These hooks 5 are thrown out immediately before sliding down the inclined way by another spring 16 which engages the surface 14 of the hooks 5.

10 The driving of the machine is effected by another bevel pinion 17 driven by a pair of spur gears, shaft 18, endless chain 19, worm 20, and motor drive 21.

I will now describe the mechanism which 15 is used in conjunction with this filling mechanism to measure a certain quantity of syrup into the bottles before they are filled with the second liquid, which in this case we assume to be carbonated water. The proportion 20 of syrup in the carbonated product is usually one in seven, that is, one ounce of syrup is usually first filled into the bottle and then six ounces of water are deposited later.

25 In most machines where bottles are fed automatically there is usually a so-called star feed which takes the bottles from the conveyor and transfers them to the filling machine proper. This star feed is shown in 30 Fig. 1 by S, also in Fig. 2. A conveyor 22 is shown in cross section in Fig. 1 and in partial plan view in Fig. 2, which brings the bottles to the star feed. While transferring from the conveyor to the filling machine table 3, the bottle describes a semi-circular pathway following the star feed, and during this part of the motion syrup is first put into the bottle by means of a device which in a certain form is patented to 40 me in my Patent No. 1,313,301. This filling device consists of a rotary pump P in my present application, and 28 of Fig. 1 in my Patent No. 1,313,301. In my present application this device is driven by bevel gear system 23 through shaft 18, and then by bevel gears 23 and spur gears 24 and 25. One or more of these gears 24 and 25 are interchangeable so as to vary the capacity of 50 the pump. There is also an interchangeable head and valve plate in this present application, 26 and 27, and 10 and 17 of the patent mentioned above, No. 1,313,301, and the hose connection for the pump to this interchangeable head.

55 As these parts are sufficiently described in my previous patent, it is not necessary to elaborate on same in this application. I will simply say that the bottles in the star feed S describe a pathway of approximately 180 degrees, which is more than sufficient to supply these bottles with the required amount of syrup. While there are only four spouts provided in this present application as against seven spouts shown in my Patent 60 No. 1,313,301 referred to above, this does

not make any difference in operation, as any number of spouts could be used if so desired.

Having described my invention what I claim and desire to secure by Letters Patent is:

1. In a filling machine, a rotary filling means, a container-feeding conveyor, rotary container-delivering means delivering containers directly from said conveyor to said filling means, a second filling means comprising a circular series of spouts rotating continuously with said delivering means, a supply conduit intermittently connected with successive ones of said spouts, and forcing means delivering substance continuously to said conduit to be discharged by said spouts into respective containers while the containers are being delivered by said delivering means. 70

2. In a filling machine, filling means, a carrier, a lifter movable to and from said filling means and carried by said carrier, a crank movable in the path of said lifter, to engage and lift said lifter toward said filling means as said lifter passes said crank, and means for driving said carrier and said crank in unison. 80

3. In a filling machine, filling means, a carrier, lifters movable to and from said filling means and carried by said carrier, a crank having a plurality of arms and movable in the path of said lifters to cause successive ones of said arms to engage and lift successive ones of said lifters toward said filling means as said lifters pass said crank, and means for driving said carrier and said crank in unison. 90

4. In a filling machine, movable filling means having a plurality of filling spouts, a carrier, lifters movable to and from respective ones of said spouts and carried by said carrier, a crank movable in the path of said lifters to engage and lift successive ones of said lifters toward said filling spouts as the respective lifters pass said crank, and means for driving said carrier, said filling means and said crank in unison. 100

5. In a filling machine, rotary filling means, a crank, a lifter raised by said crank to lift containers toward said filling means, supporting means to hold said lifter up after said lifter is raised by said crank, but leaving said crank free to descend therefrom as soon as said lifter is lifted, means to release said supporting means after it has been raised for an interval, and means for driving said filling means and said crank in unison. 115

In testimony whereof I have signed my name in the presence of two subscribing 120 witnesses.

KARL KIEFER.
